UNITED STATES PATENT OFFICE.

ROYAL D. TOMLINSON, OF MILWAUKEE, WISCONSIN, ASSIGNOR TO ALLIS-CHALMERS COMPANY, OF MILWAUKEE, WISCONSIN, A CORPORATION OF NEW JERSEY.

CONDENSER PLANT.

No. 919,266.

Specification of Letters Patent. Patented April 20, 1909.

Application filed July 25, 1907. Serial No. 385,423.

To all whom it may concern:

Be it known that I, ROYAL D. TOMLINSON, a citizen of the United States, residing at Milwaukee, in the county of Milwaukee and State of Wisconsin, have invented a certain new and useful Condenser Plant, of which the following is a specification.

This invention relates to condenser plants, and specifically it provides an arrangement of apparatus by which a single rotary pump is adapted to remove both water and air from a condenser, the arrangement of the apparatus being such that with a pump of the character described, variable quantities of water may be discharged from the condenser by said pump. The pump is required to discharge variable quantities of water on account of changes in the temperature of the cooling water which is supplied to the condenser. The temperature of the water varies within a considerable range in the countries within the temperate zones, such, for example, in the northern part of the United States and in Canada, much less water being required to condense the same amount of steam in the winter than in the summer months.

The condenser plant described by this specification and illustrated by the drawings accompanying the same deals with an arrangement of the condenser where its height with regard to the hot well is not sufficient to enable the water to be discharged by gravity, as is customary with the so-called barometric type of condensers.

It has been customary before this invention to remove water from a condenser situated with respect to the hot well as above described, by a rotary pump and to remove air from the condenser by a reciprocating pump. Reciprocating pumps are expensive in the first instance and require a great deal of attention in order that they may perform their work satisfactorily. They also require additional power. By this invention they are dispensed with and a single, simple and comparatively inexpensive pump performs the entire service.

The specific embodiments of apparatus disclosed by this specification are intended to be illustrative and to show what is considered at present the preferable form and arrangement of the apparatus, but as it is possible to practice the invention by sub-

stituting other forms of apparatus than those disclosed by the drawings, it is to be understood that the invention is not limited to the specific construction of apparatus shown and described.

On the drawings which accompany this specification and form a part thereof and on which the same reference characters are used to designate the same elements wherever they may appear in each of the several views, Figure 1 illustrates, partly in elevation and partly in section, the preferred embodiment of this invention. Fig. 2 illustrates, in plan, a detail. Fig. 3 illustrates, in elevation and partly in section, a modified arrangement of apparatus. Fig. 4 is an illustration on an enlarged scale of a part of the apparatus shown by Fig. 3. Fig. 5 illustrates a section taken on the line *a—a* of Fig. 4. Fig. 6 is an illustration similar to Fig. 4, but showing a modified arrangement of nozzle gate operating means. Fig. 7 is a transverse section taken on the line *b—b* of Fig. 6. Fig. 8 illustrates a still further modification of the apparatus shown by Fig. 1.

Referring to the drawings, the numeral 1 designates a condenser which may be of any preferred type or form, that illustrated by the drawings being what is known as a jet condenser, but this invention is not necessarily restricted to use with a jet condenser and it is not intended that it should be so restricted.

The numeral 2 designates a steam inlet, 3 the condensing water inlet, 4 the valve for controlling the spraying of the condensing water, 5 the umbrella, and 6 the dry air pipe, these parts being of any preferred construction.

The condenser is provided with lugs 7 by which it is adapted to be supported, and secured to the lower portion thereof is the feed pipe 8 for the rotary pump 9, which may be of any ordinary or preferred type, the present preference being that it shall be a centrifugal pump.

The numeral 10 designates the shaft of the pump upon which the impeller (not shown) is mounted and to which shaft the driving means, an electric motor, belt pulley, or any ordinary or preferred driving means may be secured.

The numeral 11 designates the outlet of the pump to which is secured the Y-coupling 12, (which will ordinarily be placed with the

branches of the Y in a horizontal plane but which is shown tilted by Fig. 1 of the drawings for clearness of illustration) to one branch of which is secured the sleeve 13 containing an ejector 14 terminating in a nozzle mouth, the space between the ejector and said sleeve being connected with the dry air pipe 6, the ejector being of any ordinary or preferred type whereby air will be drawn from the condenser through pipe 6 and discharged with the water which is forced by the pump 9 through the ejector 14. Secured to the sleeve 13 is the discharge pipe 15 provided with the check valve 16, the end of said discharge pipe entering the hot well 17 and extending below the normal water level in said hot well. Connected to the other branch of the Y 12, is a short pipe section 19, within which is disposed a valve 20 provided with an arm 21 secured to the spindle 22 of the valve which is extended out through the wall of said section, and to this arm is connected by the rod 23, the crank arms 25 and 26; and the pivot pin 27, the float 24 located within the condenser.

Secured to the section 19 is the discharge pipe 28, provided with the check valve 29, the end of which extends into the hot well 17 and below the normal level of the water therein, the division plate 30 being provided in the hot well between pipes 15 and 28, if the hot well is so small that the ends of said pipes are situated comparatively close together in order that air discharged through pipe 15 may not enter pipe 28 and eventually return to the condenser if the flow of water through pipe 28 should not be very rapid.

The numeral 31 designates the overflow pipe for the hot well, and the numeral 32 designates a check valve in the dry air pipe, this check valve being provided so that the water forced by the pump 9 in starting the condenser with forced injection through pipe 3 will not back up through the dry air pipe 6 into the condenser before the water has attained sufficient velocity to overcome the back pressure of the atmosphere and open check valve 16 and flow to the hot well.

The operation of the apparatus thus far described is as follows: The steam entering at 2 encounters the cold water entering through pipe 3 and sprayed by the valve 4 and the umbrella 5, and is condensed. The water of condensation and the condensing water both flow downward into pump 9 and are thrown out through the ejector 14, whereby the air is entrained through dry air pipe 6, and the commingled air and water are discharged through pipe 15 into the hot well 17, the valve 20 ordinarily remaining closed, especially during the winter season. Should, however, the water level in the condenser rise above the normal, as indicated by the line 132, by reason of more water being supplied from any cause whatever, the float

24 will rise and open the valve 22, allowing the excess of water to be discharged by the pump through pipe 28, and when the water level in the condenser falls again to normal, valve 20 will close.

The use of the ejector 14, or any equivalent apparatus for removing the air, necessitates the flow of a maximum quantity of water at all times to render the ejector efficient and effective, and if it were not for the provision of the additional pipe 28, or its equivalent, the pump 9 would be compelled to handle at all times and under all circumstances the greatest amount of water that would be required during the very hottest weather of a long hot summer, which would not be economical of power in the operation of the pump or saving of water. By, however, using an ejector for withdrawing air from the condenser, which ejector is designed to use the minimum amount of water which it may be required to discharge from the condenser and an additional discharge passage, the single pump is enabled to perform its service from minimum to maximum load while running at a constant speed and at the same time remove the air from the condenser.

An electric motor is the means ordinarily employed to actuate rotary pumps in plants of this nature, and as the speed of rotation of said motor is practically fixed and constant, the pump is required to handle different quantities of water while its speed remains practically constant.

The apparatus shown by Fig. 3 embodies the same general principles of design and operation as the apparatus disclosed by Fig. 1. Referring to Fig. 3, the numeral 100 designates the condenser, 200 the steam inlet, 300 the condensing water inlet, 400 the spraying controlling valve, 500 the umbrella, 600 the dry air pipe, and 700 lugs upon which the condenser may be supported. The condenser is open at its lower end and provided with a flange which is adapted to be secured to a T 101, the dry air pipe being provided with a flange which is secured between the flange of the T and the flange of the condenser, or in any other suitable or equivalent manner. The condenser is provided near its bottom with the aperture 102, through which water can flow from the condenser, and connected with this aperture is the pipe 103, through which the water flows to the rotary pump 104, the discharge of which is designated by the numeral 105, and which is adapted to be secured to one branch of the T 101, while the ejector nozzle 106 is adapted to be secured to the opposite branch of the T and the discharge pipe 107 extended below the surface of the water in the hot well 108, and provided with the check valve 109, is secured to the ejector nozzle 106.

Within the T 101 and extended into the ejector nozzle 106, is the contracted nozzle 130

110 through which the water discharged by the pump is forced, attaining a high velocity at the extremity of said nozzle, thereby producing an ejector effect in the space 111, with the result that the air in the condenser flows down through the dry air pipe 600 and is withdrawn by the discharge of the water. To render this arrangement of the apparatus adapted to handle different quantities of water, the nozzle 110 is made adjustable so that its outlet area may be varied. This may be effected, see Figs. 4 and 5 by the two sliding gates 112 and 113, which are adapted to be moved horizontally of said nozzle by the intermeshing gears 114 and 115, the pinions 116 and 117 secured to the shafts 118 and 119, the pinions meshing with rack teeth provided upon said gates. The end of the nozzle 110 is provided in the structure illustrated by the drawings with two oppositely disposed slots the sides of which are parallel and provided with ways within which the gates are adapted to slide, these ways being extended farther up the nozzle than the slots.

25 By Figs. 6 and 7 are illustrated an equivalent slide operating device, the slides being provided with the slotted wings 120, 121, within the slots of which pins secured to crank arms 122 and 123 are adapted to slide, said crank arms being connected respectively with shafts 124, 125, which extend out through the casing and are provided at their outer ends with cranks 126 and 127, which are in turn connected by means of pins with 35 a common actuating lever 128, pivoted to the casing.

30 The construction and arrangement of the apparatus shown by Fig. 8 is in all respects similar to that shown by Fig. 3, except that 40 the nozzle 1100 is not adjustable, the construction being such that this nozzle may be readily removed and replaced by one of a different size. The nozzle 1100 terminates in a nozzle mouth as in the aforescribed 45 modification.

The reference letter A designates a gate valve by which the quantity of cooling water flowing to the condenser may be regulated.

The construction and arrangement of apparatus described and illustrated provides a very simple and efficient condenser plant. The pump being located directly below the condenser, cannot get air bound, space is economized, a minimum of piping is required, and the dry air pipe can be made very large so as to offer the minimum resistance to the flow of the air and attenuated gases therethrough.

It will of course be understood by those versed in the art, that the amount of water supplied to a condenser of the type disclosed by this specification varies both according to the temperature of the water and the

temperature and volume of steam which enters the condenser. The valve A disclosed by the drawings will ordinarily be manipulated to control the amount of water permitted to enter the condenser only for changes of season, as the water is supplied to this type of condensers by the excess of pressure of the atmosphere above the pressure existing within the condenser, and therefore ordinary variations in the volume of steam required to be condensed are, as it were, automatically compensated for by the changes in volume of the condensing water delivered to the condenser.

A rotary or centrifugal pump of the general type disclosed by the drawings and located with respect to the condenser as shown, for example, by Fig. 1 of the drawings, while being run at a constant speed, as for example, by an electric motor, is capable of discharging any amount of water up to the maximum capacity of the pump (for the speed at which it is run) and whether the pump is discharging its maximum capacity or less than its maximum capacity, the condenser will be kept free of air and the level of the water in the condenser will be maintained constant within comparatively narrow limits.

What I claim is,—

1. The combination with a condenser provided with steam and water inlets, of a pump for removing water from said condenser, said pump being provided with a variable discharge outlet, and an air pipe communicating with the interior of said condenser and said outlet to remove air from the interior of said condenser.

2. The combination with a condenser provided with steam and water inlets and an umbrella, of a pump provided with a variable discharge outlet for removing water from said condenser, and an air pipe leading from the interior of said condenser under said umbrella to the outlet of said pump for removing air from said condenser.

3. The combination with a condenser provided with steam and water inlets, of a pump for removing water from said condenser provided with a double discharge outlet, an ejector in one of said outlets, and an air pipe affording communication between the interior of said condenser and said ejector, the other branch of said outlet being provided with a valve for controlling the thoroughfare therethrough.

4. The combination with a condenser provided with steam and water inlets, of a pump for removing water from said condenser provided with a double discharge outlet, an ejector in one of said outlets, an air pipe affording communication between the interior of said condenser and said ejector, the

other branch of said outlet being provided with a valve for controlling the thoroughfare therethrough, and means to actuate said valve according to the water level existing within said condenser.

5. The combination in a condenser having steam and water inlets and water and air discharges, of a centrifugal pump for discharge of water from the condenser, and

means for throttling the pump outlet where-¹⁰ by the air discharge is made effective.

In testimony whereof, I affix my signature in the presence of two witnesses.

ROYAL D. TOMLINSON.
